(57) **CLAIM**

The ornamental design for a medical injection needle, as shown and described.

DESCRIPTION

FIG. 1 is a front, top, and left side perspective view of a medical injection needle showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a cross-sectional view taken along line 8-8 of FIG. 7; and,

FIG. 9 is a cross-sectional view taken along line 9-9 of FIG. 7.

The dash-dash broken lines in the drawings represent portions of the medical injection needle that form no part of the claimed design. The medical injection needle is shown with a symbolic break in its length represented with dot-dash broken lines. Any portions not shown between the break lines form no part of the claimed design. The arrow broken lines in FIG. 7 are included to indicate the cross-sectional views and form no part of the claimed design.
